UNITED STATES PATENT OFFICE

2,477,004

SCREW TYPE AIR PUMP

Win W. Paget, Michigan City, Ind., assignor to
 Joy Manufacturing Company, a corporation of
 Pennsylvania

Application October 20, 1945, Serial No. 623,485

3 Claims. (Cl. 230—143)

1

My invention relates to air pumping apparatus, and more particularly to pumping apparatus of the rotary screw type.

In a rotary screw type pumping apparatus there is obtained a longitudinal thrust on the rotors by the action of the fluid on the latter. The rotors of a high speed compressor of the screw type are desirably arranged so as to provide between themselves a slight clearance which should be maintained under all loads. In order that the rotors may be prevented from moving longitudinally under the thrust of the fluid and coming into contact with each other, it is desirable that there be provided a means which operates to balance the longitudinal thrust on the rotors and to prevent any movement of the rotors relative to each other.

An object of my invention is to provide an improved pumping apparatus. Another object is to provide improved means for balancing the longitudinal thrust on the rotors of a rotary screw type compressor. Still another object is to provide improved driving gears for the rotors of a screw type compressor. Yet another object is to provide for the rotors of a screw type compressor improved driving means including intermeshing gears fixed to the rotors and having teeth arranged at angles corresponding in hand and lead to the angles of the rotors. Other objects will appear in the course of the following description.

This application is a continuation-in-part of my application, Ser. No. 452,299, filed July 25, 1942, Air pumping apparatus, and of my application, Ser. No. 458,641, filed September 17, 1942, Air pumping apparatus.

There is shown in the accompanying drawing for purposes of illustration one form which the invention may assume in practice.

In this drawing,

Fig. 1 is a side elevational view of a complete pumping apparatus.

Fig. 2 is an elevational view of the pumping apparatus as viewed from the left-hand end in Fig. 1.

Fig. 3 is an elevational view of the pumping apparatus as viewed from the right-hand end in Fig. 1.

Fig. 4 is an enlarged horizontal longitudinal sectional view on the planes of the line 4—4 of Fig. 1.

Fig. 5 is a fragmentary vertical section, with parts shown in elevation, taken on the line 5—5 of Fig. 4.

2

Fig. 6 is a vertical sectional view taken on the plane of the line 6—6 of Fig. 5.

Fig. 7 is an enlarged fragmentary sectional view taken on the line 7—7 of Fig. 5.

Fig. 8 is an enlarged cross-sectional view taken on the line 8—8 of Fig. 1.

Fig. 9 is a cross-sectional view taken on the plane of the line 9—9 of Fig. 4.

Fig. 10 is a vertical sectional view taken on the line 10—10 of Fig. 4.

There is shown in the illustrative embodiment of the invention a pumping apparatus, generally designated 1, comprising a casing part 3 containing a pair of coacting rotors 4 and 5. The rotor 4 is a male rotor and has four helically arranged lobes 7, and the rotor 5 is a female rotor and has, in the form shown, six helically arranged grooves 8 each adapted to cooperate with the lobes of the rotor 4. The casing 3 is provided with an intake chamber 10 with which an intake passage 11 provided with suitable strainer or other devices, not shown, for preventing the ingress of harmful material, communicates, and the intake chamber communicates with the right-hand, low pressure end of the rotors, and also for a substantial part of the length of the rotors communicates with the back portions thereof, so to speak, the portions at the opposite side of the plane which includes the rotor axes, from the discharge. The intake chamber 10 also includes, as shown in Fig. 10, curved recesses 10' extending substantial distances arcuately, the extent of these recesses being such that, in the illustrative embodiment shown, the intake chamber and its component recesses 10' provide intake communication with the rotor chambers over arcs of considerably more than 180°. The casing 3 is provided at the left-hand (high pressure) end of the rotors with a discharge chamber 14 which communicates with the high pressure ends of the rotor chambers, as shown in Fig. 9.

The rotors are adapted to operate with space packing; that is to say, they are maintained in such relation to each other that there is no actual contact between them. At the high pressure ends of the rotors 4 and 5 are stub shafts 15 and 16 which are mounted in bearings 18 and 19 supported by a head member 20 attached to the end of the casing 3, as by screws 21. At the low pressure ends of the rotors are stub shafts, not shown, supported by bearings mounted in an end casing portion 23 formed integral with the casing part 3. Splined to the stub shafts 15 and 16 at 24 and 25, respectively, are helical gears 26 and 27 meshing with each other and

operating to maintain the rotors out of contact with each other. The gear 26 is made up of two parts 29 and 30 which are adjusted angularly relative to each other until any backlash between the gears 26 and 27 is almost completely eliminated. While the gear portions are in these adjusted positions, the inner peripheries of the portions are grooved to receive the spline for connecting them to the stub shaft 15. The gear part 29 is shown herein as being substantially wider than the part 30 in order that it may present a tooth area for engagement by the teeth of the gear 27 sufficiently great to carry the load when the gear 27 acts as the driving gear. The helix angles of the teeth on the gears 26 and 27 are made to correspond in hand and lead to the helix angles of the rotors to which the gears are respectively fixed. Regardless of the speed at which the rotors turn, the gears operate to maintain the space packing referred to, thus preventing wear and permitting the operation of the pump at a speed far exceeding any permissible with rotors running in contact with each other. With the gear teeth formed in the manner shown, the end thrust of the male rotor (rotor 4) will be taken entirely through the timing gear teeth and transferred to the female rotor (rotor 5) when the latter rotor is the driven member. The speed of rotation of the female rotor in the arrangement shown will be somewhat less than the speed of the male rotor and it will be much easier to take the end thrust of the female rotor with a ball bearing running at the slower speed.

A drive shaft 32 is arranged in alignment with the stub shaft 15 and is provided with a cylindrical portion 33, as shown in Fig. 6, journaled on a bearing sleeve 34 surrounding a hub portion 35 of the gear 27. Keyed to the periphery of the cylindrical portion 33 of the drive shaft is a member 37 having a number of recesses 38 formed therein receiving rollers 39 which are operative, as later described, at times to effect a clutching between the member 37 and a cylindrically bored liner ring 40 keyed, as at 42, to the gear 27. The recesses 38 have relatively straight base surfaces 43 and radial surfaces 44. It will be evident that a rotation of the member 37 in a counterclockwise direction, as viewed in Fig. 6, will cause the rollers 39 to grip the liner ring 40 and drive the gear 27. The gear 26 meshing with the gear 27 will be driven in a clockwise direction, and the rotors 4 and 5 connected to the gears 26 and 27 through the shafts 15 and 16 will be driven with the gears. If the gear 27 be driven counterclockwise at a greater angular rate than the member 37, it will not be connected to that member and will turn freely in the direction mentioned, relative to it.

It will be noted (Fig. 5) that the stub shaft 15 has another shaft 46 connected to it by means of a splined connector element 47. The left-hand end of the shaft 46 is journaled in a bearing 48 carried by an enclosure plate 50, and the shaft has fixed to it a gear 51 somewhat smaller than the gear 26. A gear 52, somewhat larger than the gear 27, meshes with the gear 51 and is journaled on a bearing carried by the drive shaft 32. Arranged within a sleeve portion 54 formed on the gear 52 is a clutch mechanism, not shown, which is adapted to be applied on the supply of a fluid under pressure to an actuating means, not shown. The clutch mechanism, its actuating means, a fluid supply means for the actuating means and control means therefor are shown and described in my applications referred to above.

When the clutch is applied, the gear 52 is connected directly to the shaft 32 and drives the gear 51. The gear 52 is driven with the gear 51 and drives in turn the gear 27, the rotors 4 and 5 being driven with the gears 26 and 27. It will be seen that the gear 27 will be rotated faster than the member 37 and in the same direction with the latter, the rollers 39 being forced toward the deeper portions of the recesses 38 and permitting rotation of the gear 27 relative to the member 37.

It will be evident that the drive shaft 32 is rotated counterclockwise in Fig. 2 and that the rotors 4 and 5 turn counterclockwise and clockwise, respectively, in Fig. 8. Air taken in through the intake connection 11 is entrapped between the casing and the rotors and is progressively moved and, if it remains entrapped, compressed as it is moved to the discharge chamber 14.

It is desirable under certain conditions that no material compression of the air take place. Accordingly, there is provided a port 56 opening through the casing 3 at such a point that no compression of the air enclosed between the rotors will take place when the port is unobstructed. Air discharged through the port 56 enters a chamber 57 which communicates with a discharge conduit 58, as shown in Fig. 4. To control the port 56 there is provided a valve 60 pivotally connected to the casing 3 at 61. This valve is adapted normally to be maintained open by a spring 62 engaging at one end the wall of a member 63 which forms a portion of the enclosure for the chamber 57. The other end of the spring acts against a piston 64 fitting a bore 65 which is formed in a member 66 secured to the casing 3 in a position overlying the member 63. A piston rod 67 is connected at its opposite ends to the piston 64 and to the valve 60. The piston 64 and the member 66 cooperate in forming a servomotor to which fluid may be admitted through a passage 68. Fluid is supplied to the passage 68 under the control of means, generally designated 70, operating in response to predetermined pressure conditions. The control means is described in my above mentioned applications and, since it forms no part of my present invention, a description of the same is considered unnecessary.

As a result of my invention there is provided improved gears for driving the rotors of a pumping apparatus. The gear teeth are so formed as to balance the longitudinal thrust on the rotors produced by the fluid pumped and to eliminate substantially any rotation of the rotors relative to each other.

While there is in this application specifically described one form which the invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. In combination, in a pump, a casing having an intake opening and a discharge opening, rotors in said casing having interengaging screw threads forming pockets and arranged to form, with the casing, compression spaces, means for driving one of said rotors, and means for driving the other of said rotors from the first and for maintaining them out of contact with each other during rotation including but a single gear coaxial with and fixed with respect to one of said rotors and of the

same hand and lead as the screw threads of said rotor and a gear meshing with said single gear secured to and of the same hand and lead as the screw threads of the other rotor.

2. In combination, in a pump, a casing having an intake opening and a discharge opening, rotors in said casing having interengaging screw threads forming pockets and arranged to form, with the casing, compression spaces, means for driving one of said rotors, and means for driving the other 10 of said rotors from the first and for maintaining them out of contact with each other during rotation including but a single gear coaxial with and fixed with respect to one of said rotors and of the same hand and lead as the screw threads of said rotor and but a single two-part gear meshing with said single gear and secured to and of the same hand and lead as the screw threads of the other rotor.

3. In combination, in a pump, a casing having 20 an intake opening and a discharge opening, rotors in said casing having interengaging screw threads forming pockets and arranged to form, with the

casing, compression spaces, intermeshing gears fixed to said rotors at one end only thereof and having helix angles of the same hand and lead as the helix angles of the rotors to which they are respectively fixed, one of said gears made in two parts spaced angularly from each other so as to eliminate substantially all backlash between said gears, and means for driving one of said rotors.
